FIG. 2

FIG. 1

FIG. 4

FIG. 3

FIG.6

FIG.5

FIG. 1 is a side elevation of the boat hoist embodying my new design, the winch as shown in FIGS. 3 and 4 having been omitted from FIGS. 1 and 2 for ease of illustration and clarity respectively.

FIG. 2 is a top view of the boat hoist shown in FIG. 1, portions being broken away and omitted to indicate indeterminate length.

FIG. 3 is an end view of the boat hoist shown in FIG. 1 and FIG. 2 having thereon a winch.

FIG. 4 is a face view of the winch mounted on the boat hoist shown in FIG. 3.

FIG. 5 is a fragmentary perspective of a portion of the boat hoist shown in FIG. 1, FIG. 2 and FIG. 3 showing the lift cam linkage in enlarged scale.

FIG. 6 is a fragmentary end view of the boat hoist linkage viewed at 6-6 in FIG. 5.

It is to be understood that the structure broken away and omitted in FIG. 2 and FIG. 3 is continued throughout the width of the boat hoist.

I claim:

The ornamental design for boat hoist, as shown and described.
